AUTOMATIC CHANGEOVER REGULATOR
AND INDICATOR DEVICEAndrew R. Olson, Bartlesville, Okla., assignor to
Phillips Petroleum Company, a corporation of
Delaware

Application December 27, 1943, Serial No. 515,794

12 Claims. (Cl. 50—23)

1

This application relates to changeover devices and to pressure regulators useful in dispensing fluids under pressure and it has particular relation to such devices employed in supplying gas to domestic and commercial burners and appliances located on the property of the ultimate consumer of liquefied gas.

The use of liquefied gas for fuel has become quite common. In devising means for dispensing this gas to the stoves or burners consuming it, there are certain problems created by the economic condition and mechanical intelligence of the consumer. The consumer generally has two small tanks of liquefied gas and uses one of these tanks as a supply holding the other tank in reserve. When the first tank becomes exhausted it is desirable to immediately place the second tank in use without allowing the numerous burners and pilot lights throughout the installation to go out. The second tank being placed on supply, preferably automatically, the now empty first tank is removed at leisure when the consumer has a chance to go to the market and exchange the empty tank for a new full tank.

The closer the operation followed in the above paragraph can be duplicated automatically by the apparatus, the less likelihood of complaint on the part of the consumer. Because of the lack of mechanical skill of a few of the consumers, it is necessary that any manual control necessary be as obvious in its operation as possible and as fool-proof as possible and that there be a clear indication at all times as to which of the fuel tanks is in service and which on reserve as well as an indication of when both tanks are being drawn from or when more than one tank is being drawn from if there are more than two tanks.

One object of this invention therefore is to provide a simple, fool-proof automatic changeover regulator and indicator having automatic changeover features and manual selection of the gas cylinder to be preferentially used as the supply and clear and obvious indications of the state of the system.

Another object is to provide first stage regulation, automatic changeover, and indication means which functions with a minimum variation in pressure of the gas supplied thereby when the device is operating on the supply or on the reserve cylinder.

Another object is to provide such a control employing relatively few parts and constructing

the device to afford protection from the weather.

Other objects are to provide novel means of biasing the device so that one valve will open before another, to provide a novel connection between the operating knob and the biasing cam and to provide novel means of indicating the position of the biasing cam.

Another object is to provide an automatic changeover dispensing regulator for connecting a plurality of liquefied gas containers automatically in a selected order and adapted to supply gas at a predetermined constant pressure to at least one dispensing conduit.

Another object is to provide a suitable assembly of apparatus to provide safety and simplicity and certainty of operation in such a regulator.

Numerous other objects and advantages will be apparent to those skilled in the art upon reading the following specification and claims and looking at the accompanying drawings.

In the drawings:

Figure 1 is an elevational view of an automatic changeover regulator and indicator dispensing system embodying my invention.

Figure 2 is an enlarged elevational view of the body of the changeover device of Figure 1 with the lower portion shown in cross-section.

Figure 3 is an elevational view taken at right angles to Figure 2 of the same apparatus shown in Figure 2 with the lower part shown in elevation and the upper portion shown in cross-section.

Figure 4 is a plan view of the top of the hand adjustment knob shown in each of the preceding figures.

Figure 5 is a cross-sectional elevation taken along the line 5—5 of Figure 4 in the direction indicated by the arrow heads.

Figure 6 is a bottom view of the knob shown in Figures 4 and 5.

Figure 7 is a plan view of the cam faced piston which is shown in cross-section in Figure 3.

Figure 8 is a cross-sectional view of the cam faced piston of Figure 7.

Figure 9 is a cross-sectional view through a modified form of the friction plate employed in Figure 2.

In Figure 1 the automatic changeover dispensing system consists of a body member 11 having an adjusting knob 12 and an indicator window 13. The lower portion of body 11 is connected by conduits 14 and 15 to liquid gas containing cylinders. The number of liquid gas containing cylinders is two or more, the present liquid

gas system generally employing two cylinders (not shown).

But the number of conduits may be increased along with the number of cylinders without involving invention.

Conduit 14 ends in a connection nipple 16 which is adapted to screw into a liquid gas container and be automatically connected thereto. A back flow check valve 17 of the usual type is adapted to automatically be mechanically forced open by the final portion of the process of connecting onto the cylinder. Whenever there is no cylinder on nipple 16, check valve 17 prevents the escape of gas.

Conduit 15 has a similar nipple 18 containing a similar back pressure check valve 19, and if there were more supply conduits each of them would be similarly equipped.

An outlet conduit 21 is provided at the lower end of body 11 and if desired a base 22 may be provided at this point to support the device against the building or stand.

The outlet conduit 21 continues below the stand in a continuation 23 and leads into a so-called final stage regulator 24 which is provided with an integral safety pressure relief valve 25. From the regulator the gas passes under carefully regulated pressure through dispensing conduit 26 which may be provided with the usual connection nipple 27 or any other form of connection device.

The interior of body 11 is best shown in Figures 2 and 3.

In Figure 2 the body 11 is seen to be formed in two parts 11 and 29 secured together by a retainer ring 31. Retainer ring 31 acts to clamp a flexible diaphragm 32 between the body portions 11 and 29 in an airtight manner. Flexible diaphragm 32 is made of any highly flexible substantially gas proof material such as rubberized cotton fabric.

In the lower portion 29 there is provided a centrally located outlet passage 33 which connects with outlet conduit 21. The cavity in the upper portion of lower part 29 forms one wall of a chamber in the body and the flexible diaphragm forms another wall of this chamber. Outlet 33 leads to the chamber. Inlets 34 and 36 are provided in member 29 and in these inlets are inserted special tire valves 37. Valves 37 are the ordinary "Dill" type valves and have a spring normally keeping valve head 38 in closed position. As usual with such valves they have projecting rod 39, 40 for forcing the valve open against the force of the spring. Valves 37 have special oversize "Neoprene" seats.

As inlets 34 and 36 may supply gas through valves 37 when flushing conditions are correct and as passage 33 carries this gas away from chamber 41, it is obvious that the gas pressure in chamber 41 varies and being in excess of atmospheric pressure generally tends to force diaphragm 32 upwardly.

Resisting the upward movement of diaphragm 32 is a piston 42 shown in Figures 2, 3, 7 and 8.

The piston 42 fits loosely in and may reciprocate up and down in cylinder 43 in body 11.

Spring 44 is disposed so as to force the piston 42 down against diaphragm 32 and the gas pressure in chamber 41. The construction of piston 42 includes a non-circular (shown as square) central opening 45 and an annular spring receiving opening 46. The spring receiving opening 46 may be dispensed with without invention but is preferred because it tends to reduce the all-over

length of the device. Intermediate the ends of the piston an annular groove 47 is cut all the way around the piston to provide a groove similar to those for piston rings. No piston ring is used as the groove is for an entirely different purpose to be explained later.

The lower end of piston 42 is provided with a cam face 48. Various forms of cam faces may be employed but in the embodiment shown in the drawing the cam face consists merely of cutting the end of the piston off at an angle so that the portion near point 49 will be in advance of all the other points of the cam face and that near point 51 will be further up as the piston moves down on the diaphragm.

As the rubberized fabric of the diaphragm has a tendency to stick to metal parts with which it is long in contact it is desirable to reduce the friction between the cam face 48 of the piston 20 and the diaphragm 32. However, this is not essential to the operation in my invention but certainly is preferable. I may accomplish this reduction of friction by several means and as shown in Figure 2 and Figure 8, I may employ 25 a circular metal disc 52 having a dimple 53 pressed in its center. The dimple 53 fits in a central depression 54 provided in the center of the cam face. The cam face may also be relieved by an annular groove 55 surrounding the 30 depression 54 to reduce the friction area and allow a pocket for accumulation of any foreign matter working its way into the device. The cam face of piston 42 may be of other shapes, however, and still practice some of the features of 35 my invention although it is preferable to employ antifriction means at this point.

In Figure 9 I have shown how plate 52 may be provided with ball bearings 56, the ball bearings being retained preferably by a retainer 40 57 which may be centered by the dimple 53. The ball bearings may roll in grooves 55 which may be made to fit the balls and have a guiding effect thereon.

In order to position the low side 49 and the high 45 side 51 of piston 42 over the valves 37 so that the proper valve stem 39 or 40 will be selectively and preferentially contacted first, a manually operated knob 58 is provided. Knob 58 has an overhanging portion 59 which acts as an 50 umbrella to prevent moisture or dust from entering the device through the opening in the top of 11. On the top of knob 58 is provided a raised arrow 61 and the device is constructed and arranged so that arrow 61 always points toward 55 the cylinder which is being preferentially and selectively biased to supply the gas to the system, the other cylinders being on reserve and not being used until the cylinder on supply is exhausted.

Knob 58 is provided with a roughened portion 63 to enable a grip to be taken thereon with the fingers and an internal fin 64 by which the rotation of the knob is limited. Fin 64 could be eliminated without changing the function of the 60 device but is placed in the device because the customers like to have the control come to a definite stop as they turn it as they feel that when the knob is turned until it stops suddenly and hard that they have made the proper adjustment whereas if the knob can rotate continuously they may become confused.

Knob 58 is provided with a central shaft 65 and in the cylindrical upper portion of this shaft a groove 66 is provided to receive a lock 75 ring 67 shown in Figure 3. The lower portion

68 of the shaft is square and is preferably provided with a sharpened point 69 to aid in the assembly of the device. Sharpened point 69 may be dispensed with however, as not involved in the invention.

In order to indicate the position of piston 42 an indicator lever 71 is provided having a portion preferably painted red at 72 which will be visible when desired through window 13. Indicator 71 is pivoted to the body at 73 and has an arm 74 extending into the groove 47 to be moved up and down as piston 42 reciprocates but as groove 47 is at the same level all around rotation of piston 42 by knob 58 will not vary the position of the indicator 72. Parts 47, 74, 73 and 72 are proportioned and arranged so that indicator 72 will not appear in window 13 when none of the valves or only one of the valves 37 is open, but so that indicator 72 will be visible in window 13 when two or more (if there are more) of the valves 37 are open. The upper end of spring 44 is retained by an annular L-shaped spring retainer 76 and the spring retainer is held in place by the split ring 67.

Operation

As shown in Figure 1 the operation of the device is as follows:

Nipples 16 and 18 are screwed into liquid gas containing cylinders (not shown) and nipple 27 is connected to the dispensing conduit (not shown) which forms a continuation of dispensing conduit 26. That portion of the dispensing conduit leads to the stoves or other appliances using the gas. The gas passing to the stove or other appliance is regulated closely as to pressure by pressure regulator 24, although pressure regulator 24 may be dispensed with in some instances. If desired, a safety valve 25 may be provided to release excess pressure if the other parts of the device fail to function properly. Normally safety valve 25 never operates.

The gas from the containers passes through supply conduits 14 and 15, although, of course, more supply conduits may be provided. Each supply conduit ends in an inlet such as 34 and 36 of Figure 2 and in this inlet are located valves 37. When first connected piston 42 is in its lower-most position and gas rushes through all of the supply conduits into chamber 41. As the flow through outlet 33 is limited by the demand of the stove or other appliance the pressure rises in chamber 41 forcing diaphragm 32 and piston 42 upwardly and compressing spring 44. Soon diaphragm 32 is high enough so that the valves 37 on the less advanced side 51 of the piston are no longer engaged by diaphragm 32 and the valve rods such as 39 no longer contact diaphragm 32 and the respective valves close and remain closed until the cylinder which is on supply and whose valve rod 40 is still in contact with the diaphragm becomes exhausted.

If there is no flow through outlet 33 the gas from supply cylinder coming through valves 37 on the low side 49 of piston 42 forces diaphragm 32 and piston 42 still higher until all of the valves are closed. As gas flows out outlet 33 piston 42 urged by spring 44 returns the diaphragm 32 as the pressure in chamber 41 falls and first re-opens the valve on the low side 49.

Normally this one cylinder as shown in Figure 2 supplies gas as long as any remains in the cylinder and valve rod 40 is the only valve rod that is depressed. If the gas being drawn through 33 is taken at such a volume for a temporary period or if the liquefied gas fails to vaporize fast

enough in the cylinder connected to inlet 34 the piston moves down and opens as many additional valves as necessary to maintain the flow through 33. If this is a temporary thing the piston will again move upwardly until only one valve rod 40 opens the supply cylinder valve.

With two valves 37 low side 49 is directly under the point of arrow 61, but if four equally spaced valves 37 are used (not shown) the low side would preferably be spaced 22½ degrees away from the arrow point so that the four valves would open serially and avoid having two open at the same instant.

Obviously, pipes 14 and/or 15 can be manifolds leading to several tanks by a plurality of nipples like 16 and 18 so that each valve 37 by controlling a pipe such as 15 can control a bank of cylinders.

When the supply cylinder becomes exhausted, piston 42 moves downward and opens at least another valve placing another cylinder on supply. At this time the red warning signal 72 appears in window 13 and the consumer knows that his cylinder on supply is exhausted. He goes to market and secures another full cylinder which he places in place of the exhausted cylinder. He knows which cylinder is exhausted because arrow 61 points toward the exhausted cylinder. He could continue with the knob in the same position but as it is not known exactly how much gas remains in the reserve cylinder or cylinders he is advised to turn knob 58 so that the arrow points at one of the former reserve cylinders. Due to non-circular shaft 68 which is splined to piston 42 this turning of the knob rotates the low side 49 of piston 42 over the cylinder formerly reserved which now is placed on supply.

The operation of the device may be repeated as many times as desired, the only manual operations being those required in attaching new cylinders and turning the knob 58. Automatic change-over is provided and there is a clear indication of which cylinder is being used and a clear indication of whether more than one cylinder is being used. The latter indication when it continues over a substantial period of time indicates positively that the cylinder on supply has become exhausted and needs replenishing.

The assembly of the device shown in Figures 2 and 3 is easily accomplished. Knob 58 is inserted through the hole in the top of body 11 and spring retainer 76 is threaded over shaft 65. Then a spring 67 is threaded over shaft 65 and snaps into place in its seat 66. Spring 44 is placed in annular spring receiving groove 46 of piston 42 and raised into place in body 11 as shown and arm 71 is inserted through the opening in extension 77. When arm 71 is positioned pivot 73 is inserted. Then window 13 is placed in position and a split retaining ring 78 holds the window 13 in place.

Valves 37 having been installed in part 29 diaphragm 32 is placed on part 29 and raised into position and retaining ring 38 is screwed into place.

It is obvious that all the objects of the invention are carried out by the embodiment shown in the drawings and that a simple, fool-proof, automatic, reliable changeover regulator and indicator has been provided. The parts are few and easy to understand and operate, entry of water or foreign matter into the device is prevented and the operator can select any valve for preferential biasing so that it will be the first to open.

From the foregoing, it is believed that the construction, operation and advantages of the ap-

paratus of my instant invention will be readily comprehended by persons skilled in the art. It is to be clearly understood however, that various changes in the apparatus herewith shown and described may be resorted to without departing from the spirit of the invention as defined by the appended claims.

Having described my invention, I claim:

1. An automatic changeover regulator and indicator comprising a body having a chamber for gas under pressure, said chamber having at least two inlets and at least one outlet for gas, a flexible diaphragm forming at least a portion of one wall of the chamber, a valve in each inlet controlling the flow of gas through said respective inlet, said valves each comprising a valve operating means disposed to be contacted by said diaphragm upon failure of the pressure of the gas in said chamber, cam means rotatable in and longitudinally movable in said body disposed to contact said diaphragm on the opposite side thereof from said chamber, said cam means comprising a main cam member and a friction reducing plate contacting the diaphragm and rotatably disposed relative to the cam member, spring means urging said cam means and diaphragm against the pressure of the gas in said chamber into contact with only such of said valve operating means to open only such of said valves as the gas pressure in said chamber permits, said cam means being formed to dispose said diaphragm to contact one of said valve operating means first to open its respective valve first, means to selectively dispose said cam means to thus open a selected one of said valves first, and indicator means operated by the cam means in its movement with the diaphragm to indicate when more than one of said valves is open.

2. An automatic changeover regulator comprising a body having a chamber for gas under pressure, said chamber having at least two inlets and at least one outlet for gas, a flexible diaphragm forming at least a portion of one wall of the chamber, a valve in each inlet controlling the flow of gas through said respective inlet, said valves each comprising a valve operating means disposed to be contacted by said diaphragm upon failure of the pressure of the gas in said chamber, cam means rotatable in and longitudinally movable in said body disposed to contact said diaphragm on the opposite side thereof from said chamber, said cam means comprising a main cam member and a friction reducing plate contacting the diaphragm and rotatably disposed relative to the cam member, spring means urging said cam means and diaphragm against the pressure of the gas in said chamber into contact with only such of said valve operating means to open only such of said valves as the gas pressure in said chamber permits, said cam means being formed to dispose said diaphragm to contact one of said valve operating means first to open its respective valve first, and means to selectively dispose said cam means to thus open a selected one of said valves first.

3. An automatic changeover regulator and indicator comprising a body having a chamber for gas under pressure, said chamber having at least two inlets and at least one outlet for gas, a flexible diaphragm forming at least a portion of one wall of the chamber, a valve in each inlet controlling the flow of gas through said respective

inlet, said valves each comprising a valve operating means disposed to be contacted by said diaphragm upon failure of the pressure of the gas in said chamber, cam means rotatable in and longitudinally movable in said body disposed to contact said diaphragm on the opposite side thereof from said chamber, spring means urging said cam means and diaphragm against the pressure of the gas in said chamber into contact with only such of said valve operating means to open only such of said valves as the gas pressure in said chamber permits, said cam means being formed to dispose said diaphragm to contact one of said valve operating means first to open its respective valve first, means to selectively dispose said cam means to thus open a selected one of said valves first, and indicator means operated by the cam means in its movement with the diaphragm to indicate when more than one of said valves is open.

4. An automatic changeover regulator and indicator comprising a body having a chamber for gas under pressure, said chamber having at least two inlets and at least one outlet for gas, a flexible diaphragm forming at least a portion of one wall of the chamber, a valve in each inlet controlling the flow of gas through said respective inlet, said valves each comprising a valve operating means disposed to be contacted by said diaphragm upon failure of the pressure of the gas in said chamber, cam means rotatable in and longitudinally movable in said body disposed to contact said diaphragm on the opposite side thereof from said chamber, said cam means comprising a main cam member and a friction reducing plate contacting the diaphragm and rotatably disposed relative to the cam member, spring means urging said cam means and diaphragm against the pressure of the gas in said chamber into contact with only such of said valve operating means to open only such of said valves as the gas pressure in said chamber permits, said cam means being formed to dispose said diaphragm to contact one of said valve operating means first to open its respective valve first, and indicator means operated by the cam means in its movement with the diaphragm to indicate when more than one of said valves is open.

5. An automatic changeover regulator and indicator comprising a body having a chamber for gas under pressure, said chamber having at least two inlets and at least one outlet for gas, a flexible diaphragm forming at least a portion of one wall of the chamber, a valve in each inlet controlling the flow of gas through said respective inlet, said valves each comprising a valve operating means disposed to be contacted by said diaphragm upon failure of the pressure of the gas in said chamber, cam means rotatable in and longitudinally movable in said body disposed to contact said diaphragm on the opposite side thereof from said chamber, spring means urging said cam means and diaphragm against the pressure of the gas in said chamber into contact with only such of said valve operating means to open only such of said valves as the gas pressure in said chamber permits, said cam means being formed to dispose said diaphragm to contact one of said valve operating means first to open its respective valve first, and indicator means operated by the cam means in its movement with the diaphragm to indicate when more than one of said valves is open.

6. An automatic changeover regulator comprising a body having a chamber for gas under pressure, said chamber having at least two inlets and at least one outlet for gas, a flexible diaphragm forming at least a portion of one wall of the chamber, a valve in each inlet controlling the flow of gas through said respective inlet, said valves each comprising a valve operating means disposed to be contacted by said diaphragm upon failure of the pressure of the gas in said chamber, cam means rotatable in and longitudinally movable in said body and disposed to contact said diaphragm on the opposite side thereof from said chamber, spring means urging said cam means and diaphragm against the pressure of the gas in said chamber into contact with only such of said valve operating means to open only such of said valves as the gas pressure in said chamber permits, said cam means being formed to dispose said diaphragm to contact one of said valve operating means first to open its respective valve first, and means to selectively dispose said cam means to thus open a selected one of said valves first.

7. An automatic changeover regulator comprising a body having a chamber for gas under pressure, said chamber having at least two inlets and at least one outlet for gas, a flexible diaphragm forming at least a portion of one wall of the chamber, a valve in each inlet controlling the flow of gas through said respective inlet, said valves each comprising a valve operating means disposed to be contacted by said diaphragm upon failure of the pressure of the gas in said chamber, cam means rotatable in and longitudinally movable in said body and disposed to contact said diaphragm on the opposite side thereof from said chamber, said cam means comprising a main cam member and a friction reducing plate contacting the diaphragm and rotatably disposed relative to the cam member, and spring means urging said cam means and diaphragm against the pressure of the gas in said chamber into contact with only such of said valve operating means to open only such of said valves as the gas pressure in said chamber permits, said cam means being formed to dispose said diaphragm to contact one of said valve operating means first to open its respective valve first.

8. An automatic changeover regulator comprising a body having a chamber for gas under pressure, said chamber having at least two inlets and at least one outlet for gas, a flexible diaphragm forming at least a portion of one wall of the chamber, a valve in each inlet controlling the flow of gas through said respective inlet, said valves each comprising a valve operating means disposed to be contacted by said diaphragm upon failure of the pressure of the gas in said chamber, cam means rotatable in and longitudinally movable in said body and disposed to contact said diaphragm on the opposite side thereof from said chamber, and spring means urging said cam means and diaphragm against the pressure of the gas in said chamber into contact with only such of said valve operating means to open only such of said valves as the gas pressure in said chamber permits, said cam means being formed to dispose said diaphragm to contact one of said valve operating means first to open its respective valve first.

9. An automatic changeover regulator and indicator comprising in combination a body having a chamber, said chamber having a plurality of inlets and at least one outlet, a diaphragm forming at least a portion of one wall of the chamber, each inlet having a valve controlling flow there-

through, each valve having an operating rod extending to a point adjacent said diaphragm, a piston having a cam face engaging the diaphragm and mounted for rotation and reciprocation in the body, spring means urging the piston against the diaphragm, a turning knob splined to the piston for rotating the cam face whereby upon failure of gas pressure in said chamber said piston and diaphragm will move and engage and open at least two valves in selected order, an annular groove in the piston, an indicator pivoted in the body having one end engaged in the groove during all movements of said piston, an inspection window, the other end of said indicator being visible through said window in at least one position whereby the indicator will indicate through the window when more than one valve is open.

10. An automatic changeover regulator and indicator comprising in combination a body having a chamber, said chamber having a plurality of inlets and at least one outlet, a diaphragm forming at least a portion of one wall of the chamber, each inlet having a valve controlling flow therethrough, each valve having an operating rod extending to a point adjacent said diaphragm, a piston having a cam face engaging the diaphragm and mounted for rotation and reciprocation in the body, spring means urging the piston against the diaphragm, and a turning knob splined to the piston for rotating the cam face whereby upon failure of gas pressure in said chamber said piston and diaphragm will move and engage and open at least two valves in selected order.

11. An automatic changeover regulator comprising in combination a body having a chamber, said chamber having a plurality of inlets and at least one outlet, a diaphragm forming at least a portion of one wall of said chamber, each inlet having a valve controlling flow therethrough, said valves being normally biased to closed position, each valve having an operating portion extending to a point adjacent said diaphragm, a piston mounted for rotation and reciprocation in said body and having a cam face biased to engage said diaphragm in said reciprocation and thereby bias at least two portions of said diaphragm, selected by the rotational position of said piston in said body, to engage said operating portions and to open at least two of said valves in a selected order upon progressive failure of gas pressure in said chamber, and means for rotating said piston to select the rotational position of said cam face and thereby select which valve shall open first upon reciprocative movement of said piston in said body.

12. An automatic changeover regulator comprising in combination a body having a chamber, said chamber having a plurality of inlets and at least one outlet, a diaphragm forming at least a portion of one wall of said chamber, each inlet having a valve controlling flow therethrough, said valves being normally biased to closed position, each valve having an operating portion extending to a point adjacent said diaphragm, a piston mounted for rotation and reciprocation in said body and having a cam face biased to engage said diaphragm in said reciprocation and thereby bias at least two portions of said diaphragm, selected by the rotational position of said piston in said body, to engage said operating portions and to open at least two of said valves in a selected order upon progressive failure of gas pressure in said chamber, and means comprising a turning knob splined to said

piston for rotating said piston to select the rotational position of said cam face and thereby select which valve shall open first upon reciprocative movement of said piston in said body.
